HEADBOARD POSITIONING MEANS FOR BEDFRAMES

Leslie K. Jackson, Cleveland, Ohio, assignor to The Harvard Manufacturing Company, Cleveland, Ohio, a corporation of Ohio

Application April 9, 1953, Serial No. 347,815.

9 Claims. (Cl. 5—131)

This invention relates to headboard positioning means for bedframes, and especially to adapter means for the positioning of headboards which are wider than bedframes on Hollywood bedframes, or the like.

Many people today are changing the style of the beds which they are using in their bedrooms and are discarding the old style bedframe wherein headboards and footboards are both used on the bedframes, and are substituting therefor a Hollywood style of bedframe. However, many of such people desire to use their old headboards with the Hollywood bedframe. Also, many people even when buying a new Hollywood bedframe today also desire to have a bed headboard used with such bedframe in order to facilitate the retention of pillows and covers on the bed, and to aid in positioning bed lights and the like in close association with the bed. It usually is quite difficult to position bed headboards on Hollywood bedframes because bed headboards usually are wider than the Hollywood bedframes, and also in many instances the lower portion of the support legs of the bed headboards are of irregular configuration so that it is difficult to secure the Hollywood bedframe to the portion of the bed headboard at the same level as the Hollywood bedframe. Thus it has been found that a bed headboard can be secured to a bedframe by means of an extension member which extends vertically of the bed headboard a sufficient distance as to engage a smooth portion thereof which facilitates obtaining a desired positive or rigid engagement between the bed headboard and the bedframe means.

Yet another important problem in positioning a bed headboard upon a Hollywood style bedframe is that the bed headboard usually is desired to be "floated" on or supported by the Hollywood bedframe so that the lower ends of the support legs of a bed headboard are elevated beyond the support floor when the headboard is engaged with the bedframe.

The general object of the present invention is to provide sturdy, adjustable connection means particularly adapted for securing bed headboards to Hollywood bedframes or the like.

Another object of the invention is to provide means for positioning a headboard that is wider than a bedframe on a bedframe by means which are compact and which can readily be disguised or hidden from view when in an assembled bed.

A further object of the invention is to position a bed headboard with irregular leg surfaces at the lower portion thereof on a bedframe.

Still another object of the invention is to provide clearance between a bed headboard and positioning means for securing such headboard to a bedframe.

Another object of the invention is to position a bed headboard on a Hollywood bedframe by means of adjustably positioned connector plates that extend laterally from the bedframe and by vertically extending adjustably positioned connector members used for securing a bed headboard to the connector plates.

2

The foregoing and other objects and advantages of the invention will be made more apparent as the specification proceeds.

The present invention in general relates to a bed assembly wherein a bedframe is provided, a pair of connector plates are secured to and extend laterally from the bedframe in an adjustable manner, and support members are adjustably secured to the connector plates and are vertically adjustable with relation thereto and extend upwardly therefrom for engaging with a bed headboard.

In order to understand the present invention more completely, reference should be had to the accompanying drawings, wherein:

Fig. 1 is a perspective view of a portion of a bedframe and a bed headboard showing connecting means associated therewith embodying the principles of the invention;

Fig. 2 is a vertical section of the apparatus of the invention taken along a side rail of the bedframe immediately adjacent the end portion thereof and facing the connecting means and bed headboard; and

Fig. 3 is a horizontal section taken on line 3—3 of Fig. 2.

In detail, the present invention relates to connection means which are indicated as a whole in the drawings by the numeral 1 and which connection means are used for securing a leg 2 of a suitable bed headboard of any desired construction to a side rail 3 of a Hollywood type bedframe 4. While only portions of the bed headboard are shown in the drawing, such bed headboard is of any conventional or desired construction and has two support legs provided therefore each of which is of similar construction and with one leg being associated with each side portion of the bedframe 4. Normally the bedframe 4 is made from metal angles with the bedframe 4 suitably positioning a pair of end plates 5, only one of which is shown in the drawings, at the bed headboard engaging end of the bedframe. Usually one end plate 5 is welded, for example, to the end of each of the side rails 3 and the end plates 5 each have a pair of horizontally directed spaced parallel slots 6 provided therein.

Inasmuch as the bed headboard normally is wider than the bedframe 4, a pair of connector plates 7 is provided, one adjacent each lateral margin of the bedframe 4. Such connector plates 7 are secured to the bedframe 4, usually by bolts 8 engaging the slots 6 in the end plates 5, so that the connector plates can protrude a desirable adjustable distance laterally of the bedframe 4 to be adjusted to the actual width of the bed headboard used with the bedframe. These connector plates 7 each have an edge flange 9 provided on the margin thereof and also usually have a plurality of vertically spaced lugs 10 struck therefrom or otherwise provided thereon. These edge flanges 9 and lugs 10 are provided for snug engagement with a vertically directed support member, such as a channel 11 one of which is engaged with each of the connector plates 7. Normally the support channels 11 are bridged over the connector plates, inasmuch as the web portions of the support channels are spaced from the main support area of the connector plates by the legs of the channel being positioned in engagement with the connector plates 7. Suitable means, such as bolts 12, extend through holes formed in the connector plates and engaging with any of a number of vertically spaced holes 13 provided in the support channels 11 so that the vertical relationship of the support channels 11 with reference to the connector plates 7 can be easily varied to a desired amount of vertical protrusion or extension for the support channels 11.

Fig. 3 clearly shows how the support channels 11 are snugly positioned intermediate the edge flanges 9 and the lugs 10 to prevent any possible twisting or arcuate

movement of the support channels 11 with relation to the connector plates. Fig. 3 also brings out the fact that the connector plates 7 have a pair of parallel slots 7a therein which match with the slots 6 to provide additional lateral adjustment of the connector plates.

As another important feature of the invention, the support channels 11, or similar connector members used, have offset portions indicated at 14. These offset portions 14 extend parallel to the lower portions of the support channels 11 and are on the longitudinal axis of such support channels so that the offset portions 14 are provided for engagement with the legs 2 of the bed headboard so that clearance is provided intermediate the lower portions of the support channels 11 and the adjacent portions of the legs 2. Thus, if desired, the heads of the bolts 12 may protrude from the web of the support channels, as indicated in Fig. 3, and still be conveniently available for engagement with a wrench or similar member even after the bed of the invention is completely assembled. Any suitable means, such as screws or bolts 15, may extend through holes provided in the offset portions 14 of the support channels to engage similarly positioned holes provided in the legs of the bed headboard.

The only actions required in assembly of the bed headboard to a bedframe is to provide some holes in the legs of the bed headboard and then adjust the support channels 11 and the connector plates 7 so as to be in alignment with the legs 2 after which the support channels or associated means can be readily secured in position to float the headboard on the bedframe. After the bed assembly of the invention has been completed, normally the bed covers, springs and mattresses placed upon the bedframe 4 will disguise or cover the connection means 1 of the invention quite well. Of course, the connection means used can be attractively colored, and if desired even suitable cover means can be placed thereover to prevent the bed covers from catching on such connection means and snagging or tearing, as well as to improve the appearance of the connection means used. It should be noted that in some instance, support channels may not be used, and the connector plates 7 could engage directly with bed headboard legs. Such headboard legs would be snugly engaged between the edge flanges 9 and lugs 10. As the connection means are all adjacent of the lower portion of the bed headboard and by the bedframe 4, they are too low to be normally viewed by the average person in a room. Such connection means are of sturdy construction, and are relatively easy to install and they provide a permanent, secure mounting of a bed headboard upon a bedframe. Thus it is contended that the objects of the invention have been achieved.

While one complete embodiment of the invention has been disclosed herein, it will be appreciated that modification of this particular embodiment of the invention may be resorted to without departing from the scope of the invention as defined in the appended claims.

I claim:

1. A bed assembly comprising a bed frame, a pair of end plates on the head end of said bedframe, a pair of connector plates adapted to extend laterally from said bedframe, means adjustably connecting said connector plates to said end plates, and support channels vertically adjustably secured to said connector plates and extending upwardly therefrom for engaging a bed headboard, said connector plates having lug and flange means thereon for engaging opposed portions of said support channels to aid in preventing pivotal movement of support channels with relation to said connector plates, said support channels being positioned to bridge over a portion of said connector plates and having upper ends offset away from said bedframe but on the longitudinal axis of said channels whereby clearance is provided between a headboard secured to the upper portions of said support channels and the lower portions of said support channels.

2. A bed assembly comprising a bed frame, a pair of end plates on the head end of said bedframe, a pair of connector plates adapted to extend laterally from said bedframe, means adjustably connecting said connector plates to said end plates, and support channels vertically adjustably secured to said connector plates and extending upwardly therefrom for engaging a bed headboard, said support channels having upper ends offset away from said bedframe but on the longitudinal axis of said channels whereby clearance is provided between a headboard secured to the upper portions of said support channels and the lower portions of said support channels.

3. A bed assembly comprising a bedframe, a pair of end plates on the head end of said bedframe, a pair of connector plates extending laterally from said bedframe, means connecting said connector plates to said end plates for lateral adjustment with relation thereto, and support members vertically adjustably secured to said connector plates and extending upwardly therefrom for engaging a bed headboard.

4. Apparatus as in claim 3 wherein said connector plates have flange and lug means thereon for engaging opposed edges of said support members to position said support members securely.

5. Apparatus as in claim 3 wherein said support members have headboard engaging sections and connector plate engaging sections with the headboard engaging sections being offset from the connector plate engaging sections.

6. In a bedframe assembly, a connector plate operatively engageable with a bedframe for securing a bed headboard thereto, said connector plate having an edge flange thereon and vertically spaced lugs extending therefrom opposed to said edge flange, and a member for engaging a bed headboard positioned between and engaged by said edge flange and lugs to be at least partly positioned thereby.

7. In combination, a bedframe, means for supporting said bedframe, a bed headboard, connector plate means secured to said bedframe at lateral margins thereof, connector members of U-shape in horizontal section carried by said connector plate means and extending vertically therefrom, said connector members each having a base and a pair of opposed side portions, and means securing said bed headboard to said connector members to support said bed headboard on said bedframe, at least parts of the base portions of said connector members lying against said bed headboard to provide a bearing surface thereon, said connector members having offset portions extending away from said bedframe engaging said bed headboard to space said bed headboard from said connector plate means.

8. In combination, a bedframe, a bed headboard, connector plate means secured to said bedframe and extending laterally therefrom, connector members secured to said connector plate means and extending upwardly therefrom, said connector plate means including lug and flange means effectively engaging opposite side portions of said connector members along vertically spaced portions thereof to aid in preventing relative movement between said connector members and said connector plate means, and means securing said bed headboard to said connector members.

9. In combination, a bedframe, a bed headboard, a pair of connector plate means secured to said bedframe, a channel shaped in section connector member secured to each of said connector plate means and extending upwardly therefrom, said connector members being positioned to bridge over portions of said connector plate means, said connector plate means including lug and flange means engaging opposite side portions of said connector members along vertically spaced portions thereof to aid in preventing relative turning movement between said connector members and said connector plate means, and means se-

curing said bed headboard to said connector members to extend therebetween.
